(57) **CLAIM**

The ornamental design for a tailgate for motor vehicle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a tailgate for motor vehicle showing my new design;

FIG. 2 is a front view thereof;

FIG. 3 is a right side view thereof, the left side being a mirror image thereof; and,

FIG. 4 is a top view thereof.

The portions of the tailgate for motor vehicle shown in broken lines are for illustrative and environmental purposes and form no part of the claimed design.

1 Claim, 4 Drawing Sheets
(4 of 4 Drawing Sheet(s) Filed in Color)
